ABSTRACT OF THE DISCLOSURE

Device for inductively heating semiconductor material includes a high-frequency generator having an oscillating circuit connected in the anode circuit of a transmitting tube, and a heating circuit at least critically coupled to the oscillating circuit. The heating circuit includes a coil adapted to surround the semiconductor material for heating the same inductively, and having a capacitance up to forty times greater than the capacitance of the tank circuit.

Our invention relates to a device for inductively heating semiconductor material.

Devices are known for inductively heating semiconductor material wherein the coil of a tuned circuit, hereinafter referred to as the heating circuit, is employed as an induction heating coil, the heating circuit being coupled to an oscillating circuit, or so-called tank circuit, which is connected in the anode circuit of a transmitting tube. In order to achieve maximum power transfer or transmission, the coupling is made as strong as possible. The generator frequency is tuned to one of the slopes or limbs of the resonance curve of the heating circuit so that it is possible to control the heating power by varying the generator frequency or, on the other hand, to adjust it at a constant value by employing suitable automatic controlling means. Reference can be had to U.S. Patent No. 3,046,379 of W. Keller et al. and U.S. Patent No. 3,265,470 of W. Keller for further details of devices of the foregoing types.

Difficulties have arisen due to the fact that disturbances in the heating circuit such as, for example, flashover between the windings of the coil or between the coil and the semiconductor material cause the generator frequency to leap across to the other slope or limb of the resonance curve whereby for the most part decrease in heating power takes place. In such case however the heating power becomes changed by the automatic controlling device which further reduces it and the heating action is discontinued. In addition to the fact that readjustment of the generator frequency by the operating personnel consequently becomes necessary, the semiconductor rod which has been heated now becomes unusable due to the discontinuance of the heating action.

It is accordingly an object of our invention to provide a device for inductive heating of semiconductor material which will avoid the foregoing disadvantages of the known devices and the necessity for readjusting the generator frequency, and will minimize the production of unusable semiconductor rods.

It is a further object of our invention to provide a device for inductive heating of semiconductor material which includes a tank circuit and a heating circuit of such construction and combination that the device will have a stable performance without any failure of the heating action during a zone melting operation.

More particularly in accordance with our invention we

2

provide a heating circuit with as little as possible super-critical coupling to the oscillating or tank circuit.

With the foregoing and other objects in view, we provide in accordance with the invention a device for the inductive heating of semiconductor members comprising a high-frequency generator having an oscillating circuit connected in the anode circuit of a transmitting or oscillating tube, and a heating circuit at least critically coupled thereto, the heating circuit including an induction coil for surrounding the semiconductor material.

Whereas in the known constructions, the high-frequency voltage is increased at the tank circuit by connecting the anode of the transmitting tube to a tap of the tank circuit coil so as to accordingly render the coupling therebetween weaker, the effectiveness of such a construction is nevertheless limited because, in the case of high power generators that are operated with a high anode voltage, due to an increased high frequency voltage, flashover can take place between the windings of the tank circuit coil. Consequently, more specifically in accordance with the invention, the capacitance of the heating circuit is set at a value which is at most 40 times larger than that of the oscillating or tank circuit. Such a ratio of the capacitance of the heating circuit to that of the tank circuit has been found to ensure a completely stable performance.

Other features which are considered as characteristic for the invention are set forth in the appended claims.

Although the invention is illustrated and described herein as embodied in a device for inductively heating semiconductor material, it is nevertheless not intended to be limited to the details shown, since various modifications and structural changes may be made therein without departing from the spirit of the invention and within the scope and range of equivalents of the claims.

The construction and the method of operation of the invention, however, together with additional objects and advantages thereof will be best understood from the following description of a specific embodiment when read in connection with the accompanying single figure of the drawing which consists of a circuit diagram of the device.

45 A transmitting or oscillating tube R together with a tank circuit including a capacitor C_T and a coil L_T form a generator in delta or Y connection. A heating circuit including a capacitance C_H and an inductance L_H are coupled alternately by a capacitor C_K and a coil L_K to the tank circuit. A switch SW is adapted to be moved between two positions in one of which the capacitor C_K becomes the coupling agent for the heating circuit and in the other of which the coil L_K becomes the coupling agent for the heating circuit. The inductance L_H consists of a coil which is adapted to surround the semiconductor material such as a rod S which is to be heated in a zone melting operation, for example. With a generator frequency of 1.5 mHz., the device of our invention has the following dimensions and component values:

50 The heating coil consists of three windings having a diameter of about 30 mm. and an inductance of about 0.5 microhenry. The heating circuit capacitance therefore has a value of 18,000 picofarads (pf.). The minimum value of the tank circuit capacitance depends upon the ratio $C_H/C_T=40$, so that the tank circuit capacitance is thus 450 pf. when the heating circuit capacitance is 18,000 pf. As a practical example, a tank circuit capacitance of 1,000 pf. was selected so that stable performance was thereby ensured. The capacitance of the coupling C_K is 600 pf., for example. If the coupling is to be effected by induction, the switch SW is shifted from its position in the drawing to a position in which the inductance L_K is connected in the circuit. The inductance L_K can consist of a coil having 10 windings with a diameter of 80

55 60 65 70 75 80 85 90 95

mm. When the generator frequency is located at the capacitor limb or slope of the resonance curve of the heating circuit, it is advantageous to couple the heating circuit with the tank circuit by means of the coupling capacitor C_K , as shown in the figure. In this case, the formation of idle or reactance currents in the cable between the tank circuit and the heating circuit can be avoided. This will also apply to the case where coupling is effected by the inductance L_K when the generator frequency is located on the inductive slope or limb of the resonance curve of the heating circuit.

We claim:

1. Device for inductively heating semiconductor material, comprising a high-frequency generator having a tank circuit including a capacitance connected in the anode circuit of a transmitting tube, and a heating circuit at least critically coupled to said oscillating circuit, said heating circuit including a coil adapted to surround the semiconductor material for heating the same inductively, and having a capacitance up to forty times greater than the capacitance of said tank circuit. 15

2. Device according to claim 1, wherein said generator is tuned to a frequency located on one limb of the resonance curve for said heating circuit.

3. Device according to claim 2, wherein said tuned frequency is located on the capacitive limb of said heat- 20

ing circuit resonance curve, and said heating circuit is coupled capacitively to said oscillating circuit.

5 4. Device according to claim 2, wherein said tuned frequency is located on the inductive limb of said heating circuit resonance curve, and said heating circuit is coupled inductively to said oscillating circuit.

10 5. Device for inductively heating semiconductor material comprising a high-frequency generator having an oscillating circuit including a first capacitance and a coil connected in the anode circuit of a transmitting tube, a heating circuit including a second coil adapted to surround the semiconductor material for heating the same inductively and a second capacitance up to forty times greater than said first capacitance of said oscillating circuit, and coupling means comprising a third capacitance, a third coil and a switch actuatable for coupling said heating circuit and said oscillating circuit to one another alternately through said third capacitance and said third coil.
